UNITED STATES PATENT OFFICE.

CALVIN MARTIN, OF PEABODY, MASSACHUSETTS, ASSIGNOR TO THE NEW ERA MACHINERY COMPANY, A CORPORATION OF NEW JERSEY.

PRINTING-PRESS.

No. 905,728.

Specification of Letters Patent.

Patented Dec. 1, 1908.

Application filed February 9, 1906. Serial No. 300,215.

To all whom it may concern:

Be it known that I, CALVIN MARTIN, a citizen of the United States, residing at Peabody, in the county of Essex and State of Massachusetts, have invented new and useful Improvements in Printing-Presses, of which the following is a specification.

This invention relates to an improvement in printing presses, the object of which is to provide means for automatically changing the type, so that as a web of paper is fed through the machine to the inking mechanism, the type may be changed at each feeding movement of the paper, if desired, so as to print different letters or figures upon the paper at each feeding movement thereof.

The particular use for a machine of the character hereinbefore set forth is in printing such articles as theater tickets, in which the body of the ticket is always the same, but each ticket, as it passes through has a different seat number and location imprinted thereon, and the machine hereinafter described and illustrated is particularly adapted for printing theater tickets, but my invention is also adapted to any kind of printing in which a large number of sheets of printing is required, each sheet differing from the other either in one or more of the words printed, or in the numerals indicating the numbers of seats or dates, for instance, where a large number of circulars are to be sent out, each having the body of the circular of the same printed matter, but the address of each sheet differing. In such a case my improved mechanism is of great advantage, saving the changing by hand of the type, by means of the automatic mechanism included therein.

With the objects hereinbefore set forth to be attained, my invention consists in a printing press comprising in its construction movable type and a chart, which is preferably formed of perforated sheet material, and mechanism controlled by said chart, whereby said type may be moved into different positions relatively to the surface to be printed upon.

The invention further consists in certain improved mechanism operated by said chart for moving the type, and finally the invention consists in the combination and arrangement of parts set forth in the following specification and particularly pointed out in the claims thereof.

In the following specification I have described and in the drawings have shown a chart consisting of sheet material provided with perforations suitably located, both for the purpose of feeding the same and for actuating and controlling the mechanism by which the type is moved into the different relative positions, but it is evident that the particular form of chart is not material, as, for instance, a web of sheet material may be used with indentations or projections thereon by which the mechanism may be controlled for moving the type, and further the chart may be arranged in a cylindrical form instead of in the form of a web of sheet material without departing from the spirit of my invention.

In the machine hereinafter described and illustrated in the drawings my invention is incorporated in combination with certain inking mechanisms and mechanisms for feeding a web of paper, slitting said paper longitudinally thereof, and then cutting the same into sections transversely thereof, whereby a continuous web of paper may be printed by one set of printing mechanisms located upon a stationary frame, the printing done on this portion of the sheet being the standard portion of the printing used upon the body of the theater ticket, while immediately adjacent to this printing mechanism is arranged a rocking frame having a stationary platen arranged to coact in the printing operation with movable type, said type being in the form of circular disks and the numerals and letters formed upon the periphery of said disks. Upon this rocking frame is also supported the mechanism to rotate said disks, which mechanism is controlled by a web of perforated paper, also supported upon said rocking frame and actuated by mechanism hereinafter described. The movable type disks upon the rocking frame are supplied with ink by means of an inking roll, which, while it is supported upon the rocking frame and movable concentric with the periphery of said disks, receives its ink from an ink distributing roll, which forms a portion of an ink distributing mechanism supported upon a stationary frame, all as more fully herein-after described.

Having thus, in general, indicated the construction and the design of my improved printing press, I will now proceed to specific-

ally describe the press in which my invention is embodied.

Referring to the drawings: Figure 1 is a side elevation of a printing press embodying my invention, the same being partly broken away and shown in section for the sake of illustration, also broken away. Fig. 2 is a plan, partly in section, taken on line 2—2 of Fig. 1. Fig. 3 is a section, partly in elevation, taken on line 3—3 of Fig. 1. Fig. 4 is a side elevation, partly broken away, illustrating the rocking frame, with the type disks, chart, and mechanism controlled by said chart for operating said disks thereon, said rocking frame being shown in its raised position in readiness for the printed web of paper to be fed between the type disks and the platen. Fig. 5 is a side elevation broken away and similar to Fig. 4, illustrating the rocking frame and the parts carried thereby moved downwardly into position for the movable type to print upon the web of paper which rests upon the platen. Fig. 6 is an enlarged view of the type disks, a portion of the chart, and the mechanism controlled by said chart for operating the stops by which the type disks are located in position for printing, in side elevation partly in section. Fig. 7 is a partial plan, broken away and shown in section of the mechanism illustrated in Fig. 6. Fig. 8 is an enlarged perspective view of a portion of the rotary type disks, the same being broken away and shown in connection with the shaft upon which they are rotatably supported. Fig. 9 is a plan view of a portion of one of the charts used in connection with my improved printing press. Fig. 10 is a portion of the web of paper upon which is illustrated the printing of the tickets, one of said tickets being shown printed substantially complete, while the other tickets are shown with only that portion at the end of the ticket containing the location and number of the seat printed. Figs. 11 to 15, inclusive, illustrate portions of tickets showing the variation which may be obtained in the printing thereon by means of my improved chart mechanism for automatically changing the type by which that portion of the ticket is printed.

Like numerals refer to like parts throughout the several views of the drawings.

In the drawings, 15 is the stationary main frame of the printing press, 16 is the main driving shaft journaled in bearings in said main frame and rotated by means of suitable pulleys (not shown in the drawings). A gear 17 fast to the main shaft 16 meshes into another gear 18 fast to a shaft 19, the shaft 19 being journaled to rotate in bearings upon the main frame 15 and having fast thereto an eccentric 20 which operates an eccentric strap 21, which, in turn, imparts a reciprocatory motion to the cutter 22, by means of which, co-acting with the stationary cutter

22', the web of paper 23, upon which the printing is done is cut transversely thereof, it being understood that the same is first slitted longitudinally thereof by slitting cutters, hereinafter described. The web of paper 23 is fed into the machine in the direction of the arrow A (Fig. 1) by a rotary drum 24 and feed rolls 25. The drum 24 is fast to a shaft 26 journaled to rotate in bearings in the frame 15, and to said shaft is fastened a ratchet 27, to which an intermittent rotary motion is imparted by means of a pawl 28 pivoted to a pawl-lever 29 loosely mounted to rock upon the shaft 26. The pawl-lever 29 has a rocking motion imparted thereto by a connecting rod or link 30, pivoted at one end thereof to said pawl-lever and at the other end thereof to a stud 31, adjustably fastened by a screw 32 to a crank 33 fast to a shaft 34. The shaft 34 rotates in bearings provided in the main frame and is rotated by a bevel gear 36 which meshes into a bevel gear 35 fast to a shaft 37 journaled to rotate in a bracket 38 fast to the main frame and having fastened to its opposite end a gear 39 which meshes into the gear 17.

The web of paper 23 is slitted longitudinally thereof by the slitting cutters 40 and 41. The slitting cutter 40 is fast to a shaft 42 which has a gear 43 fast thereto and meshing into a gear 44 fast to the shaft 26. The gear 43 also meshes into another gear 45 fast to a shaft 46 journaled to rotate in bearings in the frame 15 and having fastened thereto the slitting cutters 41. It will thus be seen that the pawl 28 imparts rotary motion to the ratchet 27, said ratchet imparting a rotary motion to the shaft 26 and to the drum 24 and gear 44 fast thereto. Said gear 44 imparts rotary motion to the gear 43 and to the slitting cutters 40, while the gear 43 imparts rotary motion to the gear 45 and to the slitting cutters 41. By these slitting cutters the web of paper is divided into a plurality of strips extending longitudinally thereof, while the transverse cutters 22 22' separate said strips into sections constituting the completed ticket.

In all of the tickets for a certain theater a certain portion, viz., that included between the lines *x* and *y* (Fig. 10), is printed by printing mechanism hereinafter fully described, at the right of the machine illustrated in Fig. 1, while that portion included between the lines *y* and *z* is printed by means of the printing mechanism in the central portion of the machine illustrated in Fig. 1, and it is this portion of the ticket which is subject to the greatest amount of change of type, and these changes are made automatically in the machine, as hereinafter described, by changing the type with certain mechanism controlled by the perforated chart, hereinbefore referred to. The part 130

of the ticket between the lines x and y may be printed upon any suitable printing mechanism, as hereinafter described.

After the body of the ticket, that is, the portion between the lines x and y (Fig. 10) has been printed, as hereinafter described, the portion of the ticket between the lines y and z is printed by means of the automatically changeable type disks and mechanism for operating said type disks, which mechanism is controlled by my improved chart, all of which I will now proceed to specifically describe. The width of the ticket being divided into nine spaces, a , b , c , d , e , f , g , h , and i , as illustrated by dotted lines (Fig. 10) in the portion of the ticket included between the lines y and z , it will be understood that the spaces a and i are always left blank, while the remaining seven spaces, b , c , d , e , f , g , and h are each represented by a corresponding type disk, viz., b' , c' , d' , e' , f' , g' and h' , Fig. 8, so that by means of figures on some of these disks and letters, characters, or complete words and small type upon the others, any combination which may be liable to arise in the printing of theater tickets may be obtained by means of these type disks, which are rotated, as hereinafter described, to bring the desired predetermined letter or figure over the platen in readiness to print upon the ticket. The type disks b' , c' and d' each has formed upon its periphery the numerals 1 to 9, inclusive, and zero; the type disk e' has formed upon its periphery the first thirteen letters of the alphabet; the type disk f' the last thirteen letters of the alphabet; the type disk g' has formed upon its periphery the numerals 1 to 9, inclusive and zero and the words "Right" and "Center." The type disk h' has formed upon its periphery the numerals 1 to 9, inclusive, and zero, the word "Left" and letters "R" and "L." All of the different type disks are loosely mounted to rotate freely upon a shaft 47. The shaft 47 is journaled to rotate in bearings formed in a rocking frame 48 pivoted to rock upon a shaft 49. Said rocking frame 48 has a rocking motion imparted thereto by means of links 50, one upon each side of said frame, said links being pivotally connected at one end thereof to the shaft 47 and at the opposite end thereof to crank-pins 51 fast to cranks 52, one upon each side of the machine and pivoted to a stud 53, one of said studs fast to each side frame of the machine. The cranks 52 form one arm of each of the bell-crank levers 54, the other arms 55 of which are pivotally connected at 56 to eccentric arms 57 integral with eccentric straps 58, which eccentric straps encircle eccentrics 59 fast to a shaft 60 journaled to rotate in bearings in the frame 15. The shaft 60 is rotated by means of a gear 61 fast thereto and meshing into a gear 62 fast to a shaft 63 journaled to rotate in bearings in the frame

15. The gear 62 meshes into a spur gear 64 fast to a shaft 65 journaled to rotate in bearings in the frame 15 and having fastened thereto a bevel gear 66 which meshes into a bevel gear 67 fast to a shaft 68 journaled to rotate in a bearing 69 fast to the main frame and having fastened thereto a sprocket gear 70 which is connected by a sprocket chain 71 to another sprocket gear 72 fast to the main shaft 16.

Beneath the type disks b' , c' , d' , e' , f' , g' , and h' extends a stationary platen 73 (Fig. 6) and between each of said type disks is a friction disk 74 (Fig. 7). These friction disks are all keyed to the type disk shaft 47, so that as said type disk shaft is rocked by mechanism hereinafter described, the friction disks 74 and also the type disks will be rotated until a projection 75 upon the periphery of one of the type disks engages one of the movable steps 76 which is moved into the path of rotation and thus locks the type disk against rotation in one direction, viz., in the direction of the arrow B (Fig. 6).

Each of the type disks is operated and controlled by substantially the same mechanism, together with a perforated chart 77, so that a description of one set of mechanism will be sufficient to fully describe all of said sets of mechanism. With this understanding I will now proceed to describe the mechanism by which one of the movable stops 76 is operated. The movable stop 76 consists of a lever pivoted at 78 to a rod extending transversely across the machine and fastened to side plates 48³ which are fastened to side standards 48¹, 48² by rods 48⁴. The movable stop lever 76 is rounded at the right hand end thereof (Fig. 6) to fit in a corresponding depression 79 formed in the end of a lever 80 pivoted to a rod 81 extending transversely across the machine and fastened to the side plates 48³. The lever 80 has pivotally connected thereto a vertical rod 82 which normally is held away from the under surface of the chart 77 but may be pressed therengainst with a yielding pressure by means of a spiral spring 83, one end of which bears against a collar 84 fast to the rod 82 and the lower end of which bears against a stationary plate 85 which is fastened to the rocking frame 48. The vertical rod 82 slides in the plate 85 and also at its upper end in a plate 86, said plate 86 extending across the machine between the side standards 48¹ and 48² of the rocking frame 48 and having fastened thereto slide plates 86¹ guided in ways 87¹ formed upon the inner faces of the side standards 48¹ and 48² of the rocking frame 48. Said plate 86 has ears 87 integral therewith and projecting downwardly therefrom, to which are pivotally connected links 88 at the upper ends thereof. At their lower ends said links 88 are pivoted to arms 89, 90 and said arms are connected at their upper

ends one to the other by links 91. The arms 89 are two in number and are pivoted at 89', respectively, to the opposite side standards 48', 48² of the rocking frame 48. The arms 90 are two in number and each is pivoted at 92 to the frame of the machine and constitutes a portion of a lever 93, the lower arm 94 of said lever being provided with a friction roll 95 journaled to rotate thereon and bearing against a cam 96 and held against said cam by a spring 96'. The cams 96, two in number, are fastened to the shaft 49 and a rotary motion is imparted to the shaft 49 by a sprocket gear 97 fast to said shaft and connected by a sprocket chain 98 to a sprocket gear 99 fast to the shaft 60.

Each of the type disks is cut away, as at 100, upon its periphery (Fig. 6) for about one-half of its circumference and when the 20 type disks are in the position illustrated in Fig. 4, a shoulder 101 upon the periphery of each of said type disks bears against a stationary stop 102 extending entirely across the machine, said shoulder being formed at 25 the junction of the depressed portion of the periphery 100 and the raised portion 103 thereof, upon which portion 103 is formed the different characters or figures. At the opposite end of the depressed portion 100 to 30 that at which the shoulder 101 is located is a projection or tooth 75. It will be understood that all of the shoulders 101 bear against the stop 102 when the type disks have been rotated to the extreme of their 35 motion in the direction opposite to the arrow B and that at this time, viz., when said shoulders 101 are all resting against the stop 102, the projections 75 upon all of the type disks will be in alignment one with the other. The 40 type disks are locked in position against movement in either direction after having first been set in the proper position for printing or for not printing, as the case may be, and as hereinafter described by means of a 45 friction brake, or a locking lever 104.

The locking lever 104 extends entirely across all of the type disks and is pivoted to a rod 105 fast to the rocking frame 48. The brake lever 104 is rocked upon its pivot 105 to remove the same from contact with the periphery of the type disks by a spiral spring 106, one end of which is fastened to a bracket 107 fast to the rocking frame 48, the other end of said spring being fastened to the lever 50 104. When the rocking frame is moved upwardly from the position illustrated in Fig. 5 to that illustrated in Fig. 4, this brake lever 104 is rocked upon its pivot, as shown in Fig. 4, and drawn out of contact with the 55 periphery of the friction disks. When the rocking frame 48 descends from the position shown in Fig. 4 to that shown in Fig. 5, the outer end of the brake lever engages a stop 108 (Fig. 6) and the lever 104 is rocked on

its pivot to bring the same into contact with 65 the periphery of all of the different disks, thus locking them against rotation in either direction while the printing is being done.

As hereinbefore set forth, the upper ends of the rods 82 are brought to bear against the 70 under surface of the chart 77. Said chart is perforated with holes located in the proper position and when one of said holes is brought into alignment, by mechanism hereinafter described, with any one of the rods 82, said 75 rod is forced upwardly by its spring 83 and the lever 80 and movable stop lever 76 are rocked upon their pivots until the left hand end of the movable stop lever 76 is brought into the path of rotation of one of the projections 75 upon one of the type disks, and then when the disks are rotated said type disks are stopped by the movable stops which have been moved into the path of rotation of their respective projections 75 and will print 80 upon the web of paper which is fed through the machine, as hereinafter described, at the next downward rocking movement of the frame 48. The collars 84 fast to the rods 82, respectively, limit the distance to which the 85 rods 82 are moved upwardly by their respective spiral springs.

Immediately above the guide plate 86 and just above the chart 77 is located a stationary guide plate 109 fast at its opposite ends 95 to the rocking frame 48. This stationary plate is provided with a series of holes 110 in alignment with the rods 82. The chart 77 consists of a web of sheet material, preferably paper, a portion of which is shown in 100 enlarged scale in Fig. 9. The holes 111 are the ones through which the rod 82 pass after the chart has been intermittently fed into alignment with said rods, as hereinbefore described, while the three series of holes 105 112 provide a means by which said chart may be fed longitudinally thereof by the intermittent feeding mechanism which will now be described.

By reference to Figs. 1, 4, 5, 6 and 7 it will 110 be seen that the chart 77 is wound upon a roll or drum 113 and is unwound from said drum 113 onto a drum 114, each of said drums being journaled to rotate upon the rocking frame 48. After the chart 77 has 115 been unwound from the drum 113 and onto the drum 114, it may be reversed by placing the drum 114 in the position of the drum 113 and vice versa, or the direction of motion of the web of paper forming the chart may be 120 reversed, as hereinafter described, and the paper wound by the mechanism upon the roll 113 and off of the roll 114. The web of paper constituting the chart 77 passes from the roll 113 downwardly beneath the guide 125 rolls 115 and 116, thence partly around the feed roll 117 to the drum 114. The feed roll 117 is fastened to a shaft 118 journaled to

rotate in bearings formed in the rocking frame 48 and is provided upon its periphery with a plurality of annular rows of pins 119 Fig. 6 which align with the holes 112 in the chart 77, so that as said feed roll is given an intermittent rotary motion an intermittent feeding motion is imparted to the chart 77 longitudinally thereof. The intermittent rotary motion hereinbefore referred to of the feed roll 117 is imparted thereto by means of a pawl lever 120 journaled to rock loosely upon the shaft 118 and having a pawl 121 pivoted thereto and in engagement with a ratchet 122 fast to the shaft 118. The pawl lever 120 has a rocking motion imparted thereto by a rod 123 which is pivotally connected to said pawl lever and extends therefrom through a slide block 124 pivoted at 125 to the main frame 15. At each side of the slide block 124 and fast to the rod 123 is adjustably fastened a collar 126, so that as the rocking frame 48 is rocked upon its pivot 49 the rod 123 slides in the block 124 until one or the other of the collars 126 abuts thereagainst, whereupon further motion of the rod 123 in that particular direction being stopped, the pawl lever 120 is rocked upon its pivot and the pawl 121 causes a partial rotation to be imparted to the ratchet 122.

30 The shaft 118 has fastened thereto a gear 127 which meshes into a gear 128 rotatably mounted upon a stud 129 fast to the rocking frame 48. The gear 128 meshes into another gear 130 fast to the drum shaft 131, so that the intermittent rotation of the feed roll 117 is imparted through the gears 127, 128 and 130 to the drum 114. By removing the intermediate gear 128 from its stud 129 and placing it upon the stud 132, which stud 40 is located between the shafts 118 and 134 in frame 48, said intermediate gear 128 will rotatably connect the gear 127 to a gear 133 fast to the drum shaft 134, and then by throwing the pawl 121 out of engagement 45 with the ratchet 122 and throwing the pawl 135, also pivoted to the pawl lever 120, into engagement with the ratchet 135', the direction of feed of the chart 77 may be reversed so as to feed said chart from the drum 114 to 50 the drum 113.

An intermittent rotary motion is imparted to the shaft 47 for the purpose of actuating the type disks and moving them into the required positions by means of a gear 136 fast 55 to the shaft 47 and meshing into a segmental gear 137 formed upon one arm of a lever 138 pivoted upon the shaft 49. A rocking motion is imparted to the lever 138 by a cam slide 139 pivotally connected to said lever at 60 164 at one end thereof and at the other end thereof slotted to straddle the shaft 60. A cam roll 140 is fastened to the cam slide 139 and engages a cam 141 fast to the shaft 60. The mechanism just described for imparting 65 a rocking movement to the shaft 47, and through the friction disks 74 to the different type disks, is duplicated upon opposite sides of the machine.

Ink is carried to and distributed over the surface of the peripheries of the different 70 type disks by an inking roll 142 Fig. 6, fast to a shaft 143 journaled to rotate at the opposite ends thereof in arms 144 journaled to rock upon the shaft 47. The arms 144 are each provided with hubs, upon the periphery 75 of each of which is provided a segmental gear 145, and these segmental gears mesh into intermediate gears 146 journaled to rotate upon studs 147 fast to the rocking frame 48. The intermediate gears 146, in turn, mesh 80 into segmental gears 148 formed upon brackets 149 fast to the main frame 15, the segmental gears 148 being concentric with the median axial line of the shaft 49. As the frame 48 rocks upon its pivot the gears 146, 85 moving around the segmental gear 148, rotate and thus cause the gears 145 to rotate and hence rock the arms 144, together with the inking roll 142, around the shaft 47 as a center, so that the inking roll is brought into 90 contact with the type upon the periphery of the different type disks.

The ink distributing mechanism by which ink is supplied to the inking roll 142 consists of an ink fountain 150 provided with an ink 95 fountain 151 from which ink is taken by means of a vibrator roll 152 journaled upon levers 153 and carried by said vibrator roll to the ink distributing roll 154 with which the inking roll contacts when in the position 100 illustrated in Fig. 1. The ink distributing roll 154 is journaled to rotate in bearings in a stand 155 fast to the frame 15 of the machine and is rotated by a gear 156 which meshes into a gear 157 fast to a shaft 158 journaled 105 to rotate in bearings in the stand 155 and rotated by means of a sprocket gear 159 driven by a sprocket chain 160 which, in turn, is driven by a sprocket gear 161 fast to the shaft 34. The levers 153 have a rocking 110 motion imparted thereto in order to move the vibrator roll 152 from the ink fountain roll 151 to the ink distributing roll 154 and return as follows: A spiral spring 162 holds the vibrator roll normally in contact with 115 the ink fountain roll (see Fig. 4) and when the rocking frame descends from the position shown in Fig. 4 to that illustrated in Fig. 5, a flat spring 163, fast to the rocking frame 48, engages the outer end of each of the 120 levers 153. These springs are of greater strength than the spiral springs 162 and thus overcome the tension of said spiral springs and rock the levers 153 upon their pivots, thus moving the vibrator roll out of contact 125 with the ink fountain roll and into contact with the ink distributing roll.

The main portion of the printing upon the

face of the ticket is always the same, and this portion of the printing is performed by a printing mechanism located at the right hand end of the machine (Fig. 1) or at the end into which the web of paper 23, upon which the printing is to be done and which forms, when subdivided, separate tickets, is fed. Any suitable printing mechanism may be used for this part of the printing of the ticket, the mechanism illustrated in Fig. 1 consisting of type 165 supported upon a rocking head 166 pivoted at 167 to the frame 15 of the machine. This type prints in the usual manner and upon the upper surface of the web of paper 23, the type being brought into and out of contact with the web of paper by rocking the head 166 upon its pivot toward and away from the paper, respectively. The rocking motion referred to is imparted to the head 166 by means of links 168, one located upon each side of the machine and pivotally connected at 169 to said head at the upper end of the links, and at the lower end thereof said links are connected to crank-pins 170 fast to cranks 171, said cranks being fastened rigidly to the shaft 63. The type 165 upon the rocking head 166 is inked by means of inking rolls 172 which are carried by sprocket chains 173 over the face of the type and around into contact with the inking plate 174 by said sprocket chains, the necessary motion being imparted to the sprocket chain 173 by the idler sprocket gears 175 and by the driving sprocket gears 176. The sprocket gears 176 are rotated by means of the gear 177 fast to the shaft 178, to which shaft said driving sprocket gears are also fastened, said gear 177 being rotated by an intermediate gear 179 which meshes into a gear 180 journaled to rotate loosely upon the shaft 167. The gear 180 is fastened to a sprocket gear 181 which is driven by a sprocket chain 182, said sprocket chain being, in turn, driven by a sprocket gear 183 fast to the shaft 63.

It will be understood that in the form of my invention hereinbefore specifically described four sets of tickets are to be printed, slit and cut from the web of paper 23 as said web of paper is fed through the machine. Said web of paper 23 (Fig. 10) is divided by the slitting cutters 40 and 41 into longitudinal strips of the width of a ticket along the lines C, C, C, and said web of paper is then cut transversely along the lines x, z by the cutters 22, thus separating the strips into separate tickets. It will, therefore, be seen that for each strip included between the lines C, C there will be a series of type disks similar to those illustrated in Fig. 8. Therefore, in the present machine there will be four series of sets of type disks each set containing seven disks. Further it will be noted that there are thirteen movable stops 76 pivoted upon thirteen rods 78 for each of the different type disks, so that for one set of type disks

(seven in number) there would be ninety-one movable stop levers and for the four sets of type disks there would be three hundred and sixty-four movable stops and a corresponding number of the rods 82 which press against the under side of the chart at the proper time.

Having now specifically described my invention, I will proceed to describe the general operation of the same: The web of paper 23, upon which the tickets are to be printed, is fed into the machine in the direction of the arrow A, Fig. 1, and all of that portion of the ticket which is to be printed, with the exception of that included between the lines y and z, Fig. 10, is then printed upon the upper face of the web of paper 23 by the mechanism hereinbefore described at the right hand end of the machine in Fig. 1. The web of paper 23 is intermittently fed the required distance, viz., the length of a ticket at each feed, and simultaneously with the printing of the body of the ticket, hereinbefore referred to, another ticket is being printed between the lines y and z by the type disks b', c', d', e', f', g' and h'. The required figure or letter to be printed at a certain time is predetermined by the chart 77, the holes 111 in which are so arranged as to allow the proper rods 82 to be forced thereinto by the springs 83, thus actuating the corresponding levers 80 and movable stop levers 76 to bring the left hand end of said movable stop levers into the path of movement of the projection 75 upon the periphery of its respective type disk, see Fig. 6.

The different rods 82 are moved upwardly, as just described, in order that those which align with certain perforations in the chart shall pass through said perforations and locate the different corresponding movable stops 76, by the cam 96, which, together with the spring 96', rocks the lever 93 upon its pivot in the proper direction to move the slide plate 86 upwardly, thus allowing the rods 82 to be moved upwardly by their respective spiral springs 83 until the upper ends of said rods either rest against the bottom of the chart 77 or else pass through the perforations therein. By reference to Fig. 6 it will be seen that the rod 82 at the extreme right is in the position of a rod which has passed through one of the perforations in the chart 77, while the remaining rods 82 are resting against the bottom of said chart. On the return movement, after the printing has been done by the type disks, the plate 86 is moved downwardly and striking against the collars 84 carries all of the rods 82 downwardly to their lowermost positions, thus rocking the levers 80 and 76 upon their pivots until the movable stop levers 76 have been rocked out of the path of motion of the projections 75 upon the different type disks. As soon as the movable stops 76 have been placed, as hereinbefore described, in position to act as stops for the different type disks, said disks

are rotated by means of the cam 141, cam slide 139, lever 138 and gear 136, which mechanism rocks the shaft 47 and the friction disk 74 keyed thereto, thus rocking also 5 the type disks in the direction of the arrow B (Fig. 6) until the projections 75 upon said type disks abut against the ends of the movable stops 76 which lie in their path of movement. The type disks which are not stopped 10 in this manner continue to be rotated until the depressed portion 100, adjacent to the shoulder 101, comes into alignment with the platen. The rocking frame 48 is then brought downwardly from the position illustrated in Fig. 4 to that illustrated in Fig. 5. Said rocking frame 48 is rocked upon its pivot, as hereinbefore described, by means of the eccentrics 59, eccentric straps 58, arms 57, cranks 52 and links 50. As the rocking 20 frame 48 is moved upwardly, the inking roll 142 is carried across the face of the type, depositing ink thereon and as it moves downwardly said inking roll is moved back to the position illustrated in Fig. 4 to get a new supply 25 of ink from the ink distributing roll 154. As soon as the printing has been accomplished by the type disks, the rocking frame 48 is moved upwardly, the rods 82 are moved downwardly away from and out of the chart 30 77, and the chart is fed forward to present a new combination of perforations to the rods when they shall next be brought upwardly, as hereinbefore described. The feeding of the chart 77 has been fully hereinbefore described.

During the upward motion of the rocking frame 48 and as soon as the disks have left the surface of the web of paper 23, said disks are rocked backwardly or in the direction opposite to that indicated by the arrow B (Fig. 6) by the mechanism hereinbefore described until the shoulder 101 upon each of said disks abuts against the stationary stop 102. Just prior to the time when the type disks 45 contact with the web of paper 23, they are locked in position, as hereinbefore described, by means of the brake lever 104. After the printing is completed upon the face of the web of paper, said web of paper is fed forward to the slitting cutters 40, 41, the web of paper is slit longitudinally thereof upon the lines C, C, C, and subsequently is fed to the cutters 22, 22', by which said web of paper is cut transversely thereof upon the lines x 50 and z, thus dividing the web of paper into separate tickets.

It is evident that the number of tickets that may be printed upon this machine is only limited by the width of the web of paper 55 23 and by the number of sections into which it is divided by the slitting cutters.

If it is desired to adjust pressure of the friction disks 74 against the type disks b', c', d', e', f', g', and h', it can be very readily done 60 by means of a nut 184 Fig. 7 which has

screw-threaded engagement with the shaft 47, so that by turning said nut in the proper direction the friction disks and type disks may be more closely pressed against each other or pressed against each other with less force, thus obtaining greater or less friction by means of which the type disks may be rotated with greater or less power against any resistance to said rotation which may be opposed thereto. It will also be noted that 70 between each set of type disks a spacing collar 185 is provided by means of which the distance between two adjacent sets of type disks may be determined.

The advantages of my improved printing 80 press consist in the fact that an enormous number of tickets can be printed in a certain period of time, or, in fact an enormous number of any kind of printed matter in which it is desired to change some portion of the 85 printed matter appearing upon the face of the sheets as they pass through the machine without stopping the machine in order to change the type.

While I have described and illustrated my 90 machine as changing the type between the lines y and z, it is evident that the type which prints upon any portion of the paper being fed through may be automatically changed by increasing the number of mechanisms or 95 sets of type disks, that is, by providing more than one chart and set of type disks and the mechanism for operating the same, such as illustrated in Figs. 4 and 5. The numerals, characters, or letters across the web of paper 100 to be printed upon could be automatically changed as said web of paper is fed through the machine in the same manner as hereinbefore described with relation to that portion of said paper lying between the lines y 105 and z.

Having thus described my invention, what I claim and desire by Letters Patent to secure is:

1. In a printing press, a type disk, a chart, 110 means to rotate said disk by frictional contact, and means controlled by said chart to stop said disk at a predetermined point in its rotation, said last-named means comprising in its construction a movable member adapted to be moved into contact with said chart and away from said chart, and a second movable member adapted to be moved into and out of engagement with said disk.

2. In a printing press, a type disk, a web of 115 perforated sheet material, means to rotate said disk by frictional contact, and mechanism controlled by said sheet material to stop said disk at a predetermined point in its rotation, said mechanism comprising in its construction a movable member adapted to be moved into contact with said web and away from said web, and a second movable member adapted to be moved into and out of engagement with said disk.

3. In a printing press, a type disk, a chart, a platen, mechanism to move said disk toward and away from said platen, means to rotate said disk by frictional contact, and mechanism controlled by said chart to stop said disk at a predetermined point in its rotation, said second-named mechanism comprising in its construction a movable member adapted to be moved into contact with said chart and away from said chart, and a second movable member adapted to be moved into and out of engagement with said disk. 65
4. In a printing press, a type disk, a chart, a platen, means to rotate said disk by frictional contact, and mechanism controlled by said chart to stop said disk at a predetermined point in its rotation in alinement with said platen, said mechanism comprising in its construction a movable member adapted to be moved into contact with said chart and away from said chart, and a second movable member adapted to be moved into and out of engagement with said disk. 70
5. In a printing press, a type disk, a chart, a platen, means to rotate said disk by frictional contact alternately in opposite directions, and means controlled by said chart to stop said disk at a predetermined point in its rotation in one direction, said last-named means comprising in its construction a movable member adapted to be moved into contact with said chart and away from said chart, and a second movable member adapted to be moved into and out of engagement with said disk. 75
6. In a printing press, a type disk, a chart, a platen, mechanism to move said type disk toward and away from said platen, means to rotate said disk by frictional contact alternately in opposite directions, and means controlled by said chart to stop said disk at a predetermined point in its rotation in one direction, said last-named means comprising in its construction a movable member adapted to be moved into contact with said chart and away from said chart, and a second movable member adapted to be moved into and out of engagement with said disk. 80
7. In a printing press, a type disk, a platen, a web of perforated sheet material, mechanism to impart an intermittent longitudinal movement to said web of sheet material, means to rotate said disk by frictional contact, and means controlled by said web to stop said disk at a predetermined point in its rotation, said last-named means comprising in its construction a movable member adapted to be moved into contact with said web and away from said web, and a second movable member adapted to be moved into and out of engagement with said disk. 85
8. In a printing press, a type disk, a platen, a web of perforated sheet material, mechanism to impart an intermittent longitudinal movement to said web of sheet material to said web of sheet material, means to rotate said disk by frictional contact, and means controlled by said web to stop said disk at a predetermined point in its rotation in one direction, said last-named means comprising in its construction a movable member adapted to be moved into contact with said chart and away from said chart, and a second movable member adapted to be moved into and out of engagement with said disk. 90
9. In a printing press, a disk with type upon the periphery thereof, means to rotate said disk by frictional contact, a movable stop, a chart consisting of a web of perforated sheet material, mechanism to impart an intermittent longitudinal movement to said chart, means to rotate said disk by frictional contact alternately in opposite directions, and means controlled by said chart to move said stop into engagement with said disk to stop said disk at a predetermined point in its rotation in one direction, said last-named means comprising in its construction a movable member adapted to be moved into contact with said chart and away from said chart. 95
10. In a printing press, a disk with type and a projection upon the periphery thereof, means to rotate said disk by frictional contact alternately in opposite directions, a movable stop, a chart consisting of a web of perforated sheet material, mechanism to impart an intermittent longitudinal movement to said chart, and means controlled by said chart to move said stop into engagement with said projection at a predetermined point in its rotation in one direction, said last-named means comprising a movable member adapted to be moved into contact with said chart and away from said chart. 100
11. In a printing press, a disk with type and a projection upon the periphery thereof, mechanism to alternately rock said disk in opposite directions by frictional contact, a stationary stop adapted to engage said disk and limit the rotation thereof in one direction, a movable stop adapted to engage said projection and limit the movement of said disk in the opposite direction, a web of sheet material constituting a chart, mechanism to impart an intermittent longitudinal movement to said chart, and mechanism controlled by said chart whereby said movable stop may be moved into and out of the path of rotation of said projection. 115
12. In a printing press, a disk with type upon the periphery thereof, mechanism to rotate said disk by frictional contact, a movable stop, a web of perforated sheet material constituting a chart, mechanism to impart an intermittent longitudinal movement to said chart, a rod, and means to hold one end 120

of said rod against said chart with a yielding pressure, said rod operatively connected to said movable stop, whereby said stop may be moved into engagement with said type disk 5 and lock the same against rotation in one direction.

13. In a printing press, a disk with type upon the periphery thereof, mechanism to rotate said disk by frictional contact, a movable stop, a web of perforated sheet material constituting a chart, mechanism to impart an intermittent longitudinal movement to said chart, a rod, means to hold one end of said rod against said chart with a yielding 10 pressure, said rod operatively connected to said movable stop, whereby said stop may be moved into engagement with said type disk and lock the same against rotation in one direction, and mechanism to move said rod 15 away from said chart, whereby said movable stop may be moved out of engagement with said disk.

14. In a printing press, a disk with type upon the periphery thereof, mechanism to 20 rotate said disk by frictional contact, a lever, a web of perforated sheet material constituting a chart, mechanism to impart an intermittent longitudinal movement to said chart, and mechanism operatively connected to 25 said lever and controlled by said chart, whereby said lever may be rocked into engagement with said type disk and lock the same against rotation in one direction.

15. In a printing press, a plurality of disks 30 with type upon the periphery thereof, mechanism to rotate said disks by frictional contact, a movable stop for each of said disks, respectively, a web of perforated sheet material constituting a chart, mechanism to impart 35 an intermittent longitudinal movement to said chart, and mechanism controlled by said chart, whereby one or more of said stops may be moved into engagement each with its respective disk and lock the disks so engaged 40 against rotation in one direction.

16. In a printing press, a disk with type upon the periphery thereof, mechanism to rotate said disk, a plurality of movable stops arranged at intervals around the periphery 50 of said disk, a web of perforated paper, mechanism to impart an intermittent longitudinal movement to said web of paper, and a plurality of mechanisms controlled by said web of paper, whereby a predetermined stop may 55 be moved into engagement with said type disk and stop the same at a predetermined point in its rotation.

17. In a printing press, a plurality of disks with type upon the periphery thereof, mechanism to rotate said disks by frictional contact, a series of movable stops for each of said disks, respectively, each of said series of stops arranged at intervals around the periphery of its respective disk, a chart, mech-

anism to impart an intermittent movement 65 to said chart, and a plurality of series of mechanisms controlled by said chart, whereby any of said disks may be stopped at a predetermined point in its rotation.

18. In a printing press, a rocking frame, a type disk journaled on said frame, mechanism to rotate said type disk, an arm pivoted on the axis of said type disk, an inking roll journaled on said arm and adapted to contact with the periphery of said disk, and mechanism to rock said arm.

19. In a printing press, a rocking frame, a type disk journaled on said frame, mechanism to rotate said type disk, an arm pivoted on the axis of said disk, an inking roll journaled on said arm and adapted to contact with the periphery of said disk, and mechanism operated by the rocking of said frame to rock said arm.

20. In a printing press, a rocking frame, a type disk journaled upon said frame, mechanism to rotate said type disk, an inking roll adapted to move in a path concentric with said disk and to contact with the periphery thereof, and mechanism operated by the rocking of said frame to move said inking roll over the periphery of said disk alternately in opposite directions, in combination with an ink distributing mechanism supported upon a stationary frame and comprising 95 in its construction an ink distributing roll with which said type disk inking roll is adapted to contact at the end of its rocking movement in one direction.

21. In a printing press, a rocking frame, a type disk journaled upon said frame, mechanism to rotate said type disk, an inking roll adapted to move in a path concentric with said disk and to contact with the periphery thereof, and mechanism operated by the rocking of said frame to move said inking roll over the periphery of said disk alternately in opposite directions, in combination with an ink distributing mechanism supported upon a stationary frame and comprising 100 in its construction an ink fountain, an ink fountain roll, a vibrator roll, levers pivoted to said stationary frame upon which said vibrator roll is journaled, and an ink distributing roll with which said type disk inking roll is adapted to contact at the end of one of its rocking movements, and means operated by said rocking frame to rock said levers and move said vibrator roll from said ink fountain roll to said ink distributing roll.

22. In a printing press, a stationary frame and printing mechanism supported thereon for printing upon a web of paper, a frame pivoted upon said stationary frame, mechanism to impart a rocking movement to said pivoted frame, a platen, movable type supported upon said rocking frame, a chart, and mechanism controlled by said chart to move

said type into alinement with said platen, and mechanism to feed said web of paper from said printing mechanism on said stationary frame between the type upon said 5 rocking frame and said platen.

23. In a printing press, in combination, printing mechanism including rotatable type disks, a chart, means to rotate said disks by frictional contact, and mechanism controlled 10 by said chart to stop said disks at predetermined points in their respective rotations, whereby different combinations and arrangements of characters on said type disks may be secured, said last-named mechanism 15 comprising in its construction a plurality of members adapted to be moved into contact with said chart and away from said chart, and a plurality of members adapted to be moved into and out of engagement with said 20 disks, respectively.

24. In a printing press, in combination, a printing mechanism including rotatable type disks, a chart consisting of a web of perforated sheet material, means to rotate said 25 type disks by frictional contact, and mechanism controlled by said chart to stop said disks at predetermined points in their respective rotations, whereby different combinations and relative arrangements of characters 30 on said type disks may be secured, said last-named mechanism comprising in its construction a plurality of members adapted to be moved into contact with said chart and away from said chart, and a plurality of 35 members adapted to be moved into and out of engagement with said disks, respectively.

25. In a printing press, a rocking frame, movable type supported on said rocking frame, a stationary platen, a chart consisting 40 of a web of perforated sheet material supported upon said rocking frame, mechanism operated by the rocking of said frame to impart an intermittent longitudinal movement to said chart, and mechanism controlled by 45 said chart to move said type into alinement with said platen.

26. In a printing press, a rocking frame, movable type supported on said rocking frame, a stationary platen, a chart consisting 50 of a web of perforated sheet material supported upon said rocking frame, mechanism operated by the rocking of said frame to impart an intermittent longitudinal movement to said chart, mechanism controlled by said 55 chart to move said type into and out of alinement with said platen, and means to lock

said type against movement when in alinement with said platen.

27. In a printing press, in combination, printing mechanism including rotatable type 60 disks, a chart, means to rotate said disks by frictional contact, and mechanism controlled by said chart to stop said disks at predetermined points in their respective rotations in operative position to print, said last-named 65 mechanism comprising in its construction a plurality of members adapted to be moved into and out of engagement with said disks, respectively.

28. In a printing press, in combination, a 70 platen, printing mechanism including rotatable type disks, a chart consisting of a web of perforated sheet material, means to rotate said disks by frictional contact, and mechanism controlled by said chart to stop said type 75 disks at predetermined points in their respective rotations in operative position to print, said last-named mechanism comprising in its construction a plurality of members 80 adapted to be moved into and out of engagement with said disks, respectively.

29. In a printing press, in combination, a platen, printing mechanism including rotatable type disks, a chart, means to rotate said disks by frictional contact, and mechanism controlled by said chart to stop said type 85 disks at predetermined points in their respective rotations in alinement with said platen, said last-named mechanism comprising in its construction a plurality of members adapted 90 to be moved into and out of engagement with said disks, respectively.

30. In a printing press, in combination, a platen, printing mechanism including rotatable type disks, a chart consisting of a web 95 of perforated sheet material, means to rotate said disks by frictional contact, and mechanism controlled by said chart to stop said type disks at predetermined points in their respective rotations in alinement with said 100 platen, said last-named mechanism comprising in its construction a plurality of members adapted to be moved into and out of engagement with said disks.

In testimony whereof I have hereunto set 105 my hand in presence of two subscribing witnesses.

CALVIN MARTIN.
